UNITED STATES PATENT OFFICE.

WILLIAM H. ROLLINSON, OF RAHWAY, NEW JERSEY.

DESIGN FOR PILE FABRIC.

49,160.

Specification for Design.

Patented June 6, 1916.

Application filed March 20, 1916. Serial No. 85,527. Term of patent 3½ years.

To all whom it may concern:

Be it known that I, WILLIAM H. ROLLINSON, a citizen of the United States, residing at Rahway, Union county, New Jersey, and doing business at No. 41 Union Square, borough of Manhattan, city, county, and State of New York, have invented a new, original, and ornamental Design for Pile Fabric, of which the following is a specification, reference being had to the accompanying drawing forming part thereof.

The figure is a plan view of a piece of pile fabric showing my design.

Copies of this patent may be obtained for five cents each, by addressing the "Commissioner of Patents, Washington, D. C."

My design comprises a stripe effect, the effect produced being to cause the stripes to stand out prominently as though the outer surface was rounded.

I claim—

The ornamental design for pile fabric, as shown.

WILLIAM H. ROLLINSON.
